CLAIM

The ornamental design for a combined floor lamp with speaker, as shown and described.

DESCRIPTION

FIG. 1 is a front, right and top perspective view of a combined floor lamp with speaker, showing our design. FIG. 2 is a rear, left and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1.

FIG. 12 is an enlarged view of detail 12 in FIG. 2.

FIG. 13 is a front, right and top perspective view of a second embodiment of a combined floor lamp with speaker.

FIG. 14 is a rear, left and bottom perspective view of the second embodiment of the combined floor lamp with speaker of FIG. 13.

FIG. 15 is a front elevation view of the second embodiment of the combined floor lamp with speaker of FIG. 13.

FIG. 16 is a rear elevation view of the second embodiment of the combined floor lamp with speaker of FIG. 13.

FIG. 17 is a left side elevation view of the second embodiment of the combined floor lamp with speaker of FIG. 13.

FIG. 18 is a right side elevation view of the second embodiment of the combined floor lamp with speaker of FIG. 13.

FIG. 19 is a top plan elevation view of the second embodiment of the combined floor lamp with speaker of FIG. 13.

FIG. 20 is a bottom plan elevation view of the second embodiment of the combined floor lamp with speaker of FIG. 13.

FIG. 21 is an enlarged view of detail 21 in FIG. 13.

FIG. 22 is an enlarged view of detail 22 in FIG. 13.

FIG. 23 is an enlarged view of detail 23 in FIG. 13; and,

FIG. 24 is an enlarged view of detail 24 in FIG. 14.

(Continued)

The broken lines depict portions of the combined floor lamp with speaker that form no part of the claimed design. The dot-dash broken lines in FIGS. 1-2, 9-14, and 21-24 depict the boundaries of the enlargements that form no part of the claimed design.
